UNITED STATES PATENT OFFICE.

GEORGE L. WHIPPS, OF PORTLAND, OREGON, ASSIGNOR TO DUO-RUN REVERSIBLE WINDOW COMPANY, OF PORTLAND, OREGON, A CORPORATION OF OREGON.

WINDOW FRAME.

Application filed March 1, 1927. Serial No. 171,861.

The present invention relates to window constructions, of the type having a supplementary or sash frame mounted for turning movement within a main stationary frame, for convenience in washing the outer surfaces of the sash panels from the inside of the building, installing or removing screens, or the like.

One object of the invention is the provision of bars hinged to the lintel of the rotary sash frame and adapted to overlap the lintel of the stationary frame, with novel provisions for the automatic operation of said bars when the sash frame turns from 15 and to its normal position, and the arrangement also being such as to provide a snug fit between said bars and the frames, without objectionable protuberances or recesses.

Another object is the provision of novel 20 means for mounting the sash frame for turning movement within the main frame, and permitting the sash frame to be readily installed and removed.

A further object is the provision of a window construction of the kind indicated 25 which is improved generally in its construction and details, and which provides for tight and neat joints between the frames.

With the foregoing and other objects in 30 view, which will be apparent as the description proceeds, the invention resides in the construction and arrangement of parts, as hereinafter described and claimed, it being understood that changes can be made within 35 the scope of what is claimed, without departing from the spirit of the invention.

The invention is illustrated in the accompanying drawings, wherein—

Figure 1 is an inside elevation of the improved window construction.

Fig. 2 is a top plan view thereof with the sash frame turned to a position at right angles with the main frame.

Fig. 3 is an enlarged horizontal section on the line 3—3 of Fig. 1, portions being broken away, showing the sash frame swung slightly out of normal position.

Figs. 4, 5, and 6 are enlarged sectional views on the respective lines 4—4, 5—5 and 50 6—6 of Fig. 1.

Fig. 7 is a sectional view on the line 7—7 of Fig. 6.

The main stationary frame 12 is secured in the wall of the building, and the sash or

supplementary frame 13 is mounted for turning movement in the frame 12. As shown, the frames 12 and 13 are constructed of wood, but they may be made of metal. The sash frame 13 comprises the jambs 14, sill 15 and lintel 16, and the frame 12 comprises the jambs 17, sill 18 and lintel 19.

The sill 18 has a step bearing 20 receiving a pivot trunnion 21 secured to and depending from the sill 15, as seen in Fig. 4, and a pivot trunnion 22 upstanding from the lintel 16 is mounted in a bearing 23 secured in the lintel 19, to mount the frame 13 for turning movement about a vertical axis intermediate the jambs 17.

For conveniently placing the frame 13 within and removing it from the frame 12, the trunnion 22 is integral with a plate 24 that is disposed in the groove 25 in the lower surface of the lintel 16 in which the parting strip 26 is fitted, said parting strip being 70 one of those disposed in the frame 13, in the usual manner, between the upper and lower sashes 27 and 28 respectively. Thus, in placing the frame 13 within the frame 12, with the parting strip 26 and plate 24 removed, the trunnion 21 is readily positioned in the bearing 20, and after the frame 13 is moved to position, the plate 24 is placed in the groove 25 and the trunnion 22 inserted 75 upwardly through an aperture leading from the groove 25 to the upper surface of the lintel 16, so as to cause said trunnion to enter the bearing 23. The parting strip 26 may then be placed in the groove 25. When removing the frame 13 the parting strip 26 is 80 removed, thereby permitting the plate 24 and trunnion 22 to be removed.

The frame 13 is provided in the jambs thereof with vertical spaces 29 in which the sash weights 30 are movable, and said sash 95 weights are of rectangular form, as seen in Fig. 3.

Stop bars 31 are secured to the jambs 17 for the contact of the frame 13 when it is moved to normal position within the frame 12, and stop bars 33 are secured to the frame 13 to contact with the jambs 17. Weather strips 32 of rubber or other suitable material are secured to the jambs 17 adjacent to the stop bars 31 for the tight engagement of the frame 13, to prevent the leakage of air or rain between the jambs of the two frames. A weather strip 34 is secured on the sill

18 to contact with the lower surface of the sill 15 to prevent the elements from passing between the sills, and a similar weather strip 35 is secured to the lower surface of the lintel 19 to bear on the lintel 16 to prevent the elements from passing between the lintels. As seen in Fig. 4, the upper surfaces of the sills 15 and 18 slope outwardly, with the outer edge portion of the sill 15 overhanging the sill 18 beyond the weather strip 34, so that the sills will effectively shed rain and moisture therefrom.

A stop bar 36 is hingedly mounted, as at 37, at the inner edge of the sill 18 to swing upwardly and outwardly to a position along the lower end of the frame 13, in order to prevent the frame 13 from turning, and to also provide a neat finish between the sills of the frames at the inner side of the window.

For convenience in swinging the bar 36 upwardly, when it is desired to turn the frame 13, a lifter 38 is slidably vertically in a guide 39 carried by the sill 15 of the frame 13, and has a finger 40 at its lower end disposed under the bar 36, as seen in Fig. 4, and said lifter has a finger piece or hook 41 at its upper end, whereby the lifter may be conveniently raised so that the finger 40 thereof swings the bar 36 upwardly and inwardly. The bar 36 may then be swung downwardly out of the path of the sill 15 when the frame 13 is turned.

Outer and inner stop bars 42 are hingedly connected, as at 43, with the lintel 16 of the frame 13 and are adapted to swing upwardly into rabbets 44 in the lintel 19 of the frame 12 to provide a snug and neat joint between the two frames. The bars 42 are swung upwardly yieldingly by means of coiled springs 25 connecting said bars and extending across the lintel 16 within grooves or channels 46 formed in said lintel, or the lintel may have bores or openings extending therethrough to accommodate said springs.

In order that the bars 42 will be swung downwardly smoothly when the frame 13 is turned from normal position and will swing upwardly snugly into engagement with the frame 12 when the frame 13 is returned to normal position, the bars 42 are formed with rabbets 47 extending from those ends thereof which move under the lintel 19 when the frame 13 is swung from normal position. The rabbets 47 are formed with oblique walls 48 which have a cam action against the corresponding edges of the lintel 19 when the frame 13 is turned out of normal position. It will be noted that the rabbets 47 provide clearances between the edges of the lintel 19 and the walls 48 of said rabbets, permitting the frame 13 to turn slightly before the walls 48 contact with the edges of the lintel 19, and further turning movement of the frame

13 will cause the bars 42 to be swung downwardly so as to pass under the lintel 19.

The ends of the bars 42 opposite to the rabbets 47 are adapted to abut the upper end portions of the stops 33 when the frame 13 is in any position, and the ends 50 of the bars 42 from which the rabbets 47 extend are cut obliquely so as to move into wedging engagement with the upper end portions of the stop bars 31 that are cut away and bevelled, as at 49, as seen in Fig. 6, for the engagement of the bevelled ends 50 of said bars 42. The clearance between the walls 48 of the rabbets 47 and edges of the lintel 19 are sufficient to permit the bars 42 to swing upwardly into place in overlapping relation with the lintel 19, or within the rabbets 44 thereof, and as the bars 42 swing upwardly into place the ends 50 thereof come into tight contact with the bevelled portions 49 of the stop bars 31. Thus, as seen in Fig. 1, the joint between the bars 31 and 42 is neat and plain. In fact, both the inner and outer sides of the window are plain and neat, without any objectionable protuberances or recesses such as would mar the appearance of the window or would otherwise be objectionable.

With the present construction, it is only necessary to swing the bar 36 inwardly and downwardly, to permit the frame 13 to be turned, so that the outer side of the sash panels may be cleaned, or the window screen applied to or removed from the outer side of the frame 13. The bars 42 are automatically swung when the frame 13 is turned from and returned to normal position, and the stop bars 31 and 33 are fixed to the respective frames.

The improvements may be embodied in a window construction made of metal as well as a construction composed of wood, as shown.

Having thus described the invention, what is claimed as new is:

1. A window comprising a main frame, a supplementary frame mounted for turning movement therein about a vertical axis, and a spring influenced bar hinged to the lintel of the supplementary frame to swing upwardly and overlap the lintel of the main frame, said bar having a rabbet extending from one end to provide a clearance between the bar and the lintel of the main frame.

2. A window comprising a main frame, a supplementary frame mounted for turning movement therein about a vertical axis, and a spring influenced bar hinged to the lintel of the supplementary frame to swing upwardly and overlap the lintel of the main frame, said bar having a rabbet extending from one end to provide a clearance between the bar and the lintel of the main frame, said end of the bar being bevelled, and the main frame having a stop bar for the con-

tact of the supplementary frame and provided with a bevelled portion for the contact of said end of the first named bar.

3. A window comprising a main frame, a supplementary frame mounted for turning movement therein about a vertical axis, bars hinged to the opposite edges of the lintel of one frame to overlap the lintel of the other frame, and springs connecting said bars to swing them toward one another to overlap the second-named lintel.

4. A window comprising a main frame, a supplementary frame mounted for turning movement therein about a vertical axis, stop bars hinged to the lintel of the supplementary frame at the opposite edges thereof and adapted to swing upwardly into overlapping relation with the lintel of the main frame, and springs connecting said bars for 20 swinging them upwardly.

5. A window comprising a main frame, a supplementary frame mounted for turning movement therein about a vertical axis, stop bars hinged to the lintel of the supplementary frame at the opposite edges thereof and adapted to swing upwardly into overlapping relation with the lintel of the main frame, and springs connecting said bars for swinging them upwardly, each of said bars having 30 a rabbet extending from one end to provide a clearance between said bar and the lintel of the main frame.

6. A window comprising a main frame, a supplementary frame mounted for turning movement therein about a vertical axis, stop bars hinged to the lintel of the supplementary frame at the opposite edges thereof and adapted to swing upwardly into overlapping relation with the lintel of the main frame, and springs connecting said bars for swinging them upwardly, each of said bars having a rabbet extending from one end to provide a clearance between said bar and the lintel of the main frame, said ends of the 40 bars being bevelled, and the main frame having stop bars for the contact of the sup-

plementary frame and formed with bevelled portions against which said ends of the first-named bars are seatable when said first-named bars move into overlapping relation 50 with the lintel of the main frame.

7. A window comprising a main frame, a supplementary frame therein, pivot means between the sills of said frames, and a pivot trunnion inserted upwardly through the 55 lintel of the supplementary frame and engaging the lintel of the main frame.

8. A window comprising a main frame, a supplementary frame therein having a lintel with a lower parting strip groove, pivot 60 means between the sills of said frames, and a plate seated upwardly in said groove and having an upstanding trunnion extending through the lintel of the supplementary frame and engaging the lintel of the main 65 frame.

9. A window comprising a main frame, a supplementary frame mounted for turning movement therein about a vertical axis, a stop bar hingedly connected with the sill of 70 the main frame to swing to a position adjacent to the sill of the supplementary frame to maintain the supplementary frame in normal position, and means movably carried by the supplementary frame and having a 75 portion to engage under said bar for swinging said bar upwardly from said position.

10. A window comprising a main frame, a supplementary frame mounted for turning movement therein about a vertical axis, a stop bar hingedly connected with the sill of 80 the main frame to swing to a position adjacent to the sill of the supplementary frame to maintain the supplementary frame in normal position, and a lifter carried by said 85 supplementary frame and having a finger to be disposed below said bar for swinging said bar upwardly and away from the supplementary frame when said lifter is raised.

In testimony whereof I hereunto affix my 90 signature.

GEORGE L. WHIPPS.
